MODULATION ANALYZER

David Grimes and William S. Barden, Staten Island, N. Y., assignors to Radio Corporation of America, a corporation of Delaware

Application April 26, 1932, Serial No. 607,536

8 Claims. (Cl. 179—171)

Our present invention relates to methods of measuring percentage modulation, and more particularly to an improved method of measuring percentage modulation of modulated signal energy.

While it is often convenient to measure radio frequency or intermediate frequency gain with an unmodulated signal, the case of a modulated signal is important because of receiver sensitivity and over-all performance measurements. For this reason, and due largely to the considerable amount of interest which is frequently noted in the matter of signal structure, the present invention concerns itself with signal analysis in general, and with a method of measuring percentage modulation in the usual cases. As is well known, a standard modulated signal comprises a carrier and two side components whose properties can be determined by considering an ideal modulator.

In such a case, a pure carrier potential is applied in the control grid circuit of a single stage amplifier whose output circuit is tuned to the carrier frequency, and is sufficiently broad to present a tuned impedance which is substantially a pure resistance of constant value over a band of frequencies including the two side components. This ideal modulator is conceived to exhibit a strictly linear relation of radio frequency output to the low frequency control potential applied for example in the screen or plate circuit. The modulating potential is superimposed on the steady screen or plate voltage.

It can, then, be theoretically and physically demonstrated that in this ideal case the gain of the stage is controlled at the modulating frequency, modifying the output at any instant with an intended and systematical variation of relatively low periodicity, although this rate of variation need not be restricted to a relatively slow time function. Mathematical analysis of the aforementioned ideal case reveals that modulation has not altered the carrier, but has developed two side components which are equal in magnitude, and bear frequency symmetry with respect to the carrier.

This method of considering the effect of modulation on the carrier, with consequent development of two side components of equal magnitude, has limited utility, but is a convenience in some cases, especially where certain complications arise. Occasionally, a vectorial conception of modulation is of great assistance. Thus, each of the carriers, upper side component and lower side component may be represented by a vector

having a constant magnitude, and rotating with a constant angular velocity.

It is customary, and proper, to employ the carrier vector as a reference line, consider it to be stationary, and regard the side component vectors to rotate in opposite directions with $2\pi f$ as their angular velocity; that is to say, these vectors may be considered as rotating at the audio modulating frequency, instead of at their absolute radio frequencies. From this conception there can be derived the subsequent conclusion that the aforementioned three vectors have a resultant vector instantaneous magnitude.

Now, we have found that as far as observable results with any known device as concerned, the degree of modulation can be determined by measuring the side components and the carrier, individually. Such a method is employed in the signal analyzer of the present invention wherein a piezo-electric crystal is utilized as a means of sufficiently high selectivity to discriminate against the carrier and the lower side component, for example, when the upper side component is being measured.

Briefly, it may be stated that the present signal analyzer embodies a device for adjusting a local oscillator frequency to beat with any desired signal component at the frequency of crystal resonance. Thus, the output of a conventional first detector contains a particular component which is selected by the crystal, amplified, and measured by a tube voltmeter. This process is performed individually on the carrier and each side component, thus determining their relative magnitudes.

Of course, the tube voltmeter is accurately calibrated, and the process of detection, amplification, and selectivity, is not appreciably subject to variation in intensity level between intended limits.

It can be demonstrated that the degree of modulation can be expressed, according to the present method by the following expression:

$$M = \frac{\text{Total side component magnitude}}{\text{Carrier magnitude}}$$

This fraction is readily evaluated from the data afforded by the signal analyzer, and, thus, the modulation indicating device on a signal generator may be calibrated, due regard to certain following considerations being paid. These are interesting from the standpoint of signal structure in general, as well as from the standpoint of modulation measurement.

It is well recognized that many signal genera-

tors depart from ideal production of a modulated carrier wave. Hence, it is essential to consider the effects of these departures on the simple analyzer method of measuring percentage modulation 5, as disclosed in the present application. A signal generator may introduce frequency modulation, in conjunction with the legitimate amplitude modulation, and may introduce side component phase distortion due to resonance phenomena 10 embodied in the design for good reasons. Harmonics of the modulating tone may be present, at the modulator. Any, or all, of these extraneous effects are capable of causing the foregoing definition of M to be in error.

15 Suppose a signal generator to have side component phase distortion as its only essential "defect" as far as modulation is concerned, and consider the modulated signal to exist in a selective circuit with the carrier "on resonance". The side components are "off resonance", and therefore suffer a phase shift relative to themselves in a pure resistance device. However, it can be readily demonstrated that the matter of phase distortion due to usual tuned circuits, which are 20 purely resistive to the carrier and resistive and reactive to the upper and lower side components, is regarded as being of no consequence. Of course, side component attenuation, relative to the carrier in the resonator, decreases the percentage modulation.

Since phase is ignorable, the analyzer reveals the actual percentage modulation of delivered signal. At 400 cycles per second, side component attenuation due to resonance is probably unimportant in most cases. In the case of 5000 cycles per second modulation, as involved in receiver over-all fidelity testing, side component attenuation due to resonance may decrease the original percentage modulation by 25%. The present analyzer determines the actual percentage modulation of the radio frequency output, which is the desired information.

When harmonics of the modulating tone are impressed, the system being otherwise ideal for 45 example, each modulating component sets up a pair of radio frequency side components independently of any other modulating components present. It can be shown that in the absence of frequency, or phase, modulation, the usual harmonic content present in the modulating potential is not a source of material error, except when receiver over-all distortion measurements are to be taken. In this case the analyzer of the present invention may be used to advantage as a means 50 of investigation.

Of course, pure monotone modulation is striven for. Frequency, or phase, modulation effects are commonly referred to in connection with signal generators, particularly when the oscillator is 55 modulated directly. These phenomena are most easily avoided by modulating a radio frequency stage. The presence of frequency modulation can be readily determined by the analyzer described in the present application, by virtue of unequal magnitudes of corresponding side components.

It remains only to determine whether or not the foregoing definition of M is valid when the side components are unequal, as is not infrequently the case. It can be shown that the definition given for M is valid for the usual cases 70 where the amount of frequency modulation is not great enough to cause over-neutralization of a side component. At very low modulating frequencies a side component may be over-neutralized. The extent of inequality of the principal

side components may be adjusted by varying the modulating frequency, and, of course, exact neutralization of one side component can be thus produced when the frequency modulation effect is exactly in phase, or exactly out of phase, with the amplitude modulation effect. At lower modulating frequencies, over-neutralization obtains, and at higher modulating frequencies under-neutralization obtains.

In the latter case, the signal structure is plainly that of a standard signal as regards phase. In the former case, lower than critical modulating frequency, one of the side components is reversed in polarity due to over-neutralization. The variable modulating frequency procedure is, thus, seen to be a convenient and trustworthy method for arriving at the orientation which is in some cases necessary to rigorously affirm signal structure, and evaluate M by means of the data afforded by the simple analyzer of the present invention.

Hence, it may now be stated that it is one of the prime objects of our present invention to provide a signal structure and percentage modulation analyzer which essentially consists of a sharply discriminating resonator disposed between a frequency changer device and a beat frequency amplifier, the resonator being utilized as a means of sufficiently high selectivity to discriminate against the carrier and one of the side components when the other side component, for example, is being measured.

Another important object of the present invention is to provide a signal wave analyzer, readily adapted for the determination of percentage modulation of a signal wave, the analyzer being constructed and arranged to measure the ratio of total side component magnitude of the wave to the carrier magnitude of the wave, the said ratio comprising a measure of the percentage modulation of the wave, the analyzer consisting of a local oscillator electrically coupled with a frequency changer, an intermediate frequency amplifier, a subsequent tube voltmeter, a sharply selective resonator being utilized between the output of the frequency changer and the input of the intermediate frequency amplifier.

Another object of our present invention is to provide a signal wave analyzer which essentially comprises an electrical receiving circuit operating on the heterodyne principle, and utilizing a piezo-electrical coupling device between the frequency changer circuit and the beat frequency utilizing circuit, a pair of coupled resonant circuits being employed subsequent to the piezo-electric coupling to eliminate inherent spurious resonance crystal frequencies separated from the desired resonant frequency of the piezo-electric coupling device by a relatively slight number of cycles.

Still other objects of the present invention are to improve generally, the simplicity, accuracy, and efficiency of signal wave analyzers, and to especially provide a signal wave percentage modulation analyzer which is not only durable and reliable in operation, but economically manufactured and assembled.

The novel features which we believe to be characteristic of our invention are set forth in particularity in the appended claims, the invention itself, however, as to both its organization and method of operation will best be understood by reference to the following description taken in connection with the drawing in which we have indicated diagrammatically one circuit arrange- 75

ment whereby our invention may be carried into effect.

Referring now to the accompanying drawing, which diagrammatically shows an analyzer capable of carrying out the aforementioned objects and purposes, there is shown a pair of terminals 1, 2 adapted to be coupled to the radio frequency input to be measured. In other words, the terminals 1, 2 may be connected to the output of a signal generator, or they may be even connected to an antenna circuit where the signal wave to be analyzed is radiated from the signal wave source. An electron discharge tube 3, preferably of the screen grid type, has its control electrode, or grid, adjustably connected to the terminal 1, while the cathode is connected to ground through a path including a conductor 4, an inductance coil 5, and a condenser 6, the latter having a magnitude of about 0.1 mf., the condenser being shunted by a resistor 7 having a magnitude of about 30,000 ohms. The resistor 7 supplies bias for the grid of tube 3.

A grounded variable resistor 8, functioning as a gain control device, is shunted across the input electrodes of tube 3, the resistor having a magnitude of about 3 megohms, the grid of tube 3 being adjustably connected to a point on resistor 8. In order to check the "drift" of the analyzer, a switch 9 is connected in shunt with the adjustable resistor 8. The anode of tube 3 is connected to the positive terminal of a source of potential (not shown) capable of supplying 135 volts to the anode.

The connection between the said source and the anode of tube 3 comprises a path consisting of the conductor 10, the resistor 11 and the conductor 12. The screen grid electrode of the tube 3 is connected, through a path which includes the conductor 13, to a point on the aforementioned source of potential which maintains the screen grid electrode at a potential of 67.5 volts. It will be noted that the negative terminal of the aforesaid potential source is noted by the designation "B—" and that it is connected to ground.

The tube 3, and its associated circuits, comprises the frequency changer device of the analyzer, local oscillations being impressed upon the frequency changer from a local oscillation source which comprises an electron discharge tube 14, preferably a 238 pentode tube having an indirectly heated cathode, it being pointed out that all the tubes shown in the present analyzer employ indirectly heated cathodes. The pentode oscillator circuit described herein is more fully disclosed in a copending application Serial No. 592,461, of W. S. Barden, filed February 12, 1932. The anode of tube 14 is connected to be operated at a potential of 135 volts through a path which includes the conductor 15, the coil 17, the conductor 13' and the conductor 12.

The control electrode of tube 14 is grounded through a path which includes the feed-back inductance coil 16 and the lead 15', it being noted that the coils 16 and 17 are coupled, as at M₁. A variable condenser 18 is connected in shunt with the coil 17, a vernier condenser 19 being shunted across the condenser 18, while a second vernier condenser 20 is simultaneously shunted across the condenser 18. A switch 21 is connected in series with the condenser 19, while a second switch 22 is connected in series with the vernier condenser 20. The function of these switches, main and vernier condensers will be described at a later point. The use of the above

named pentode oscillator circuit results in substantial elimination of undesired second harmonics and zero grid current flow in the oscillator.

The cathode of the tube 14 includes in series therewith a grid biasing resistor 24, having a magnitude of about 850 ohms, the resistor being shunted by a fixed condenser 25 of a magnitude of about 0.2 mf. The screen electrode of tube 14 is connected by a lead 12' to the 135 volt source, 10 and the suppressor grid is connected to the cathode within the tube in the usual manner. Oscillations produced in the tuned circuit 17, 18, are impressed on the coil 5, through coupling M₁, thus injecting the local oscillation frequency into 15 input of tube 3.

The output circuit of the tube 3 is coupled to the input circuit of the intermediate frequency amplifier tube 26 through a sharply selective resonant circuit. The sharply selective resonant circuit comprises a resistor 11, the high potential side of the resistor being connected to the conductor 10, and the low potential side of the resistor being connected to the conductor 12. The control electrode of tube 26, and the indirectly heated cathode 25 of tube 26, are coupled across resistor 11, by means of a piezo-electric crystal 29, preferably of quartz. The quartz crystal 29 is cut to be resonant to a frequency of 50 kilocycles, and is disposed between four metallic electrodes, a pair 30 of the said 30 electrodes being disposed adjacent one end of the crystal, while the remaining pair 30' are disposed at the opposite end of the crystal.

The coupling arrangement of the crystal 29, and its location with respect to the four electrodes are well known to those skilled in the art, and it is well recognized that such a coupling arrangement is sharply selective with respect to the frequency transmitted through the coupling. The pair of electrodes 30' are connected to opposite sides of the resistor 11 through a fixed direct current blocking condenser 28, each of the fixed condensers having a magnitude of 0.00025 mf. The remaining pair of electrodes 30 are connected to opposite sides of a resistor 31, the latter being connected in shunt between the control grid and the grounded side of the cathode of tube 26, the resistor 31 having a magnitude of about 3 megohms.

The screen grid electrode of tube 26 is connected by means of a conductor 32 to the conductor 13, the latter being connected to the screen grid electrode of tube 3, and is thus arranged to have a positive potential of 67.5 volts applied thereto.

It will be noted that the anode of tube 26 has a positive potential of 135 volts applied thereto through conductors 12 and 33, the primary coil 34 of the transformer coupling M₂, and the conductor 35. The indirectly heated cathode of tube 26 includes, in the grounded leg thereof, the usual biasing resistor 36 having a magnitude of about 400 ohms, the resistor being shunted by a fixed condenser 37 having a magnitude of 0.1 mf. It will be noted that the anode supply potential lead 12 and the screen grid potential supply lead 13 are shunted to ground by the fixed condensers 38 having magnitudes of 0.2 mf. In order to prevent undesired radio frequency coupling between the output and input circuits of tubes 3 and 26, there is disposed a grounded metallic shield 39 between the electrodes 30' and 30.

The output circuit of tube 26 and the input circuit of the electron discharge tube 39, which is preferably a triode detector having an indi-

rectly heated cathode, are coupled by a sharply resonant circuit comprising the primary coil 34 of transformer M_2 , shunted by an adjustable condenser 40, and the secondary coil 41 shunted by 5 an adjustable condenser 42. A source of negative grid bias voltage C is connected between the grounded side of the cathode of tube 39 and the grid of the tube so that the tube 39 and associated circuits function as a second detector. The 10 anode circuit of tube 39 includes the micro-ammeter 43 to indicate the carrier, or side, component magnitudes, the anode being connected by a conductor 44 to a point on the source of anode potential which will maintain the anode 15 at 135 volts. The meter 43 is shunted by a variable resistor 45 including in series therewith a source of current 46.

Considering, now, the operation of the analyzer shown in the drawing and described in detail 20 heretofore, the local oscillator frequency is adjusted by means of the main condenser 18 and either of the vernier condensers 20 or 19 to beat with any desired signal component impressed across the input electrodes 1, 2, at the frequency 25 of crystal resonance. Thus, assume that a carrier is modulated by a monotone, and that it is desired to measure the percentage modulation of the resulting modulated carrier. In the case of more than one modulating tone, additional side bands 30 can be measured and total modulation determined. The magnitude of the carrier would first be determined by adjusting the large condenser 18 to the setting which will beat with the carrier frequency to produce an intermediate frequency 35 of approximately 50 kilocycles, the frequency at which the width of the crystal 29 is resonant. Any operation of the crystal at the thickness resonance which would be likely to occur at some frequency of the oscillator is precluded by the resonant 40 shunt path 10' 11' to ground. This path is resonant to the thickness frequency of the crystal. At this setting of the condenser 18, the reading on the meter 43 is taken, and this reading indicates the magnitude of the carrier.

45 It should be noted that each of the condensers 40 and 42 are adjusted to resonate their coupled resonant circuits to the desired intermediate frequency. The function of the coupled resonant circuits between tubes 26 and 39 is to remove any 50 spurious responses which might be caused by multiple crystal resonant frequencies near the legitimate crystal resonance. These undesired resonant peaks result from slight irregularities in grinding of the crystal but are far enough off 55 proper resonance to be effectively removed by the resonant coupled circuits.

The tube 39 and its associated circuits actually 60 comprise a tube voltmeter, and the function of the variable resistor 45 and potential source 46 is to balance out of the micro-ammeter 43 all permanent direct current so that the meter will be free to indicate slight changes in the plate current caused by the incoming carrier or side bands. Assume, now, that the side component 65 magnitudes are to be measured. One of the switches 21 or 22 is closed and the associated vernier condenser is adjusted to the desired side component. At the desired side component frequency the reading of meter 43 is taken. This 70 reading gives the magnitude of said side component frequency without the value of the carrier, as the carrier frequency is off the crystal resonance frequency and cannot pass through the crystal.

In this case, the local oscillator has been adjusted to that frequency which will beat with the

side component frequency to produce the 50 kilocycle intermediate frequency. It will be found in employing the analyzer that one of the vernier condensers can be employed for the lower frequency side bands, while the other one can be 5 employed for the higher frequency side bands. After the meter reading of the carrier C has been obtained, and the reading of the lower side component S_1 alone and the upper side component S_2 have alone been secured, the percentage modula- 10 tion is equal to:

$$M = \frac{\sqrt{S_1} + \sqrt{S_2}}{\sqrt{C}} \times 100.$$

The square root of each direct current reading 15 is used in this formula because the tube 39 is very nearly a true square law detector throughout the intended range of applied signal intensities.

It will thus be seen that the output of the first 20 detector tube 3 contains a component which is selected by the crystal, amplified, and measured by the tube voltmeter. This process is performed individually on the carrier and each side component, thus determining their relative magnitudes. The tube voltmeter may be accurately 25 calibrated. If not, such a device, when square law, as is usual, gives the square of the proper reading. Hence, the actual readings are obtained by a square root process.

While we have indicated and described one arrangement for carrying our invention into effect, it will be apparent to one skilled in the art that our invention is by no means limited to the particular organization shown and described, but that many modifications may be made without departing from the scope of our invention as set forth in the appended claims.

What we claim is:

1. A method of determining percentage modulation of a modulated carrier wave which includes beating the modulated wave with local oscillations to produce a predetermined beat frequency, transmitting the beat frequency energy through a sharply selective path, measuring the intensity of the beat frequency energy, and adjusting the frequency of the local oscillations to selectively produce said beat frequency energy for the carrier frequency and the side band frequency in the absence of the carrier frequency, consecutively.

2. A method of analyzing a modulated carrier wave including heterodyning the carrier of the modulated carrier wave with local oscillations of a frequency sufficient to produce a predetermined intermediate frequency, amplifying the latter, detecting the amplified intermediate frequency energy, indicating the intensity of the detected energy, and later producing intermediate frequency energy by heterodyning said local oscillations with either of the side components only of said modulated wave.

3. A signal analyzer comprising a screen grid tube having an input circuit and an output circuit, means in the input circuit of the tube adapted to be connected to a signal wave so as to be analyzed, a local oscillator comprising a tube having its output circuit coupled to the input circuit of said screen grid tube, an intermediate frequency amplifier comprising a screen grid tube provided with an input circuit and an output circuit, a coupling network connected between the output circuit of said first screen grid tube and said second screen grid tube and com-

prising a piezo-electric coupling device resonant to the desired intermediate frequency, a tube voltmeter circuit comprising an electron discharge tube provided with an input circuit coupled to the output circuit of said intermediate frequency amplifier tube, the output circuit of said electron discharge tube including a visual indicator.

4. A signal analyzer comprising a screen grid tube having an input circuit and an output circuit, means in the input circuit of the tube adapted to be connected to a signal wave so as to be analyzed, a local oscillator comprising a tube having its output circuit coupled to the input circuit of said screen grid tube, an intermediate frequency amplifier comprising a screen grid tube provided with an input circuit and an output circuit, a coupling network connected between the output circuit of said first screen grid tube and said second screen grid tube and comprising a piezo-electric coupling device resonant to the desired intermediate frequency, a tube voltmeter circuit comprising an electron discharge tube provided with an input circuit coupled to the output circuit of said intermediate frequency amplifier tube and said second screen grid tube and comprising a piezo-electric coupling device resonant to the desired intermediate frequency, the output circuit of said electron discharge tube including a visual indicator, and a tuned circuit in the output circuit of said intermediate frequency amplifier tube, said last mentioned tuned circuit and the tuned input circuit of said electron discharge tube being coupled and resonant to said desired intermediate frequency.

5. A signal analyzer comprising a screen grid tube having an input circuit and an output circuit, means in the input circuit of the tube adapted to be connected to a signal wave so as to be analyzed, a local oscillator comprising a tube having its output circuit coupled to the input circuit of said screen grid tube, an intermediate frequency amplifier comprising a screen grid tube provided with an input circuit and an output circuit, a coupling network connected between the output circuit of said first screen grid tube and said second screen grid tube and comprising a piezo-electric coupling device resonant to the desired intermediate frequency, a tube voltmeter circuit comprising an electron discharge tube provided with an input circuit coupled to the output circuit of said intermediate frequency amplifier tube, the output circuit of said electron discharge tube including a visual indicator and a tuned circuit, resonant to an undesired crystal thickness frequency, connected in the output circuit of said first screen grid tube and arranged in shunt with said piezo-electric coupling device.

6. A signal analyzer comprising a screen grid tube having an input circuit and an output circuit, means in the input circuit of the tube adapted to be connected to a signal wave so as to be analyzed, a local oscillator comprising a tube having its output circuit coupled to the input circuit of said screen grid tube, an intermediate fre-

quency amplifier comprising a screen grid tube provided with an input circuit and an output circuit, a coupling network connected between the output circuit of said first screen grid tube and said second screen grid tube and comprising a piezo-electric coupling device resonant to the desired intermediate frequency, a tube voltmeter circuit comprising an electron discharge tube provided with an input circuit coupled to the output circuit of said intermediate frequency amplifier tube, the output circuit of said electron discharge tube including a visual indicator, and said local oscillator tube including in its input circuit a variable tuning condenser and one or more vernier condensers.

7. In combination in a percentage modulation analyzer, a source of local oscillations comprising an electron discharge tube having an input circuit including a device for varying the frequency of oscillations produced, a frequency changer circuit including an electron discharge tube having its input circuit coupled to said oscillator output circuit, a beat frequency amplifier, a piezo-electric element arranged to couple the output circuit of said frequency changer tube and the input of said amplifier, said piezo-electric device being sharply resonant to a desired beat frequency, a circuit resonant to a frequency different from said beat frequency coupled to said piezo-electric device and arranged to prevent it from resonating at a frequency other than said beat frequency, a detector circuit including an ammeter having a graduated scale in its output, and a pair of resonant circuits, tuned to said beat frequency, arranged to couple the output of said amplifier to the input of said detector circuit, and means connected in the output circuit of said detector for adjusting the operation of said ammeter.

8. A device for measuring the percentage modulation of a modulated carrier wave by comparing the readings of a graduated ammeter comprising, the combination of a vacuum tube frequency changer having an input and an output circuit, a second detector having an input and an output circuit, means for impressing a carrier frequency modulated by a single audio frequency on the input circuit of said frequency changer, a source of local oscillations coupled to the input circuit of said frequency changer, a circuit network coupling the output circuit of said frequency changer to the input circuit of said second detector and including a piezo-electric crystal resonant at a relatively low frequency and whose selectivity is such that it will transmit the beat frequency formed by the local oscillator and carrier frequencies but will block the beat frequency formed by the local oscillator and the sum frequency of the carrier and modulation frequencies, and a graduated ammeter connected in the output circuit of the second detector.

DAVID GRIMES.
